UNITED STATES PATENT OFFICE.

WILLIAM S. HUTCHINSON, OF BETHLEHEM, PENNSYLVANIA.

DERRICK.

Application filed May 18, 1921. Serial No. 470,719.

To all whom it may concern:

Be it known that I, WILLIAM S. HUTCHINSON, a citizen of the United States, and a resident of Bethlehem, in the county of 5 Northampton and State of Pennsylvania, have made a new and useful Invention in Derricks, of which the following is a specification.

My invention relates to derricks and consists in an improved sectional mast and boom and in a novel attaching spider for the mast guy ropes and an improved mounting for a guy rope spider.

One object of my invention is to provide 15 a derrick which may be knocked down for transportation without undue difficulty and which may be adapted for different heights of mast and lengths of boom for different jobs or for different stages of the same job.

Another object is to provide a simple 20 means for securing the guy ropes to the top of the mast which permits the derrick to rotate freely and which distributes the guy rope strains more evenly over the upper 25 end of the mast. I also desire to eliminate the protruding angles and shackles which are present in the usual derrick mast and which are in the way and likely to be injured when the derrick is being transported 30 and set up.

My invention is illustrated in the accompanying drawings in which Figure 1 is an elevation of a complete derrick; Fig. 2 is a 35 section, on an enlarged scale, through the center of the top of the derrick and detailing my improved spider and preferred method of mounting same, and Fig. 3 is a top view of the spider.

The derrick mast is composed of structural steel box girders 1, 2, 3 and 4 and the 40 derrick boom is composed of similar girders 5, 6, 7 and 8. The end girders of both mast and boom are perfectly tapered as shown and the intermediate girders vary in length. 45 Each girder is united with its adjacent girder by splice plates 9 and the assembly of adjacent girders by these splice plates is of such nature that the girders may be disassembled from each other and reassembled

50 either in the same relation or in other relations. For instance, girder 2 or 3 or both may be omitted, shortening the mast, and the boom length may be similarly shortened by omitting girders 6 and 7 or it may be 55 lengthened by insertion of one or both girders 2 and 3.

This construction, besides affording a desirable variation in the capacity of the derrick, is advantageous in the transportation of same. As is well known, complete derrick masts and booms are often longer than 60 railway cars and two or even three cars are sometimes required to transport them. With the permanently assembled derrick members of large dimensions, this awkward 65 and often difficult use of cars is a necessity. With the construction shown herein, the boom and mast may be readily knocked down and the entire derrick loaded on a single car.

The upper end of girder 4 terminates in 70 an end plate 18 firmly secured to each side of the girder. Spaced below plate 18 is a diaphragm 10 similarly secured. Plate 18 and diaphragm 10 are provided with central 75 openings which form spaced journal bearings for a gudgeon pin 11 which extends beyond the end of the mast and journals a spider member 12.

Spider 12 forms the means for securing 80 the guy ropes to the mast. It is preferably a thick disk of cast iron cored out at 13 to provide hook-shaped portions 14 facing upwardly and adapted to enter the usual guy 85 rope eye. The lower surface of the spider rests on end plate 18 and the coring is well spaced from the central hub-like portion 15 whereby the spider is given such a mounting 90 on the mast that any strain from the guy ropes is fairly distributed about the latter instead of being concentrated at one place. It will be noted that the circumference of the spider is beveled inwardly from plate 18 and that a cover plate 16 is secured 95 on the spider top by machine screws 17.

These features avoid injury to the spider 100 when the mast is knocked down and form a marked improvement over the loose links usually secured to the top of a derrick mast and which are always in the way as they project some distance beyond the sides of the mast. Obviously, cover plate 16 retains the guy ropes when the latter are in place as well as protecting and stiffening the 105 spider hooks 14.

The circular shape of the spider is not essential nor are the particular means for journaling it to permit the derrick to rotate on its base, but the general features which eliminate the undue projection of guy-rope 110 securing elements and enable the spider to function as described are advantageous and

novel and I contemplate mechanical modifications in their use.

Likewise the shape, dimensions and number of the girder sections are immaterial to 5 my invention so long as the essential features of interchangeability and variation in derrick height and reach are maintained.

Having described my invention fully above, I now claim:

- 10 1. The combination with a derrick mast, of a spider rotatably mounted on said mast and provided with a series of upwardly extending lugs adapted to receive guy-rope loops, and a cover secured across the tops of 15 said lugs for inclosing the spaces formed therebetween.
2. The combination with a derrick mast, of a disc-shaped spider rotatably mounted on said mast and provided with a series of 20 upwardly extending circumferential lugs adapted to receive guy-rope loops and an annular cover secured across the tops of said lugs and inclosing the spaces formed therebetween.
- 25 3. The combination with a derrick mast, of a gudgeon pin mounted in spaced bearing plates at the top of said mast, a disc-shaped spider provided with a relatively wide hub portion for rotatably engaging said gudgeon 30 pin, and a series of circumferential upwardly extending lugs formed on said spider for receiving guy-rope loops and an annular

cover secured to the tops of said lugs and seating on said hub portion around said gudgeon pin.

4. The combination with a derrick mast, of a gudgeon pin mounted in spaced bearing plates at the top of said mast, a disc-shaped spider provided with a relatively wide hub portion for rotatably engaging said gudgeon 40 pin, a bearing face formed at one end of said hub portion and adapted to seat on one of said bearing plates, a series of circumferential upwardly extending lugs formed on said spider for receiving guy-rope loops and an 45 annular cover secured to the tops of said lugs and seating on said hub portion around said gudgeon pin.

5. The combination with a derrick mast, of a gudgeon pin mounted in spaced bearing 50 plates at the top of said mast, a disc-shaped spider provided with a relatively wide hub portion for rotatably engaging said gudgeon pin, a bearing face formed at one end of said hub portion and adapted to seat on one of said bearing plates and a series of circumferential upwardly extending lugs formed on said spider for receiving guy-rope loops.

In testimony whereof, I have hereunto subscribed my name this 12th day of April, 60 1921.

WILLIAM S. HUTCHINSON.
